ELECTRO-CHEMICAL MACHINING SYSTEM
Richard C. Johnson, 11713 Lytle St., Silver Spring, Md.,
and John W. Sawyer, 4519 18th St., North Arlington,
Va.

Filed Feb. 23, 1955, Ser. No. 490,158

1 Claim. (Cl. 204—143)

(Granted under Title 35, U.S. Code (1952), sec. 266)

The invention described herein may be manufactured 10 and used by or for the Government of the United States of America for governmental purposes without the payment of any royalties thereon or therefor.

This invention relates generally to a method and an apparatus for removing metal from a member to thereby 15 reduce the same to a predetermined shape and size and in particular to novel apparatus for the electro-chemical removal of metal.

The art of metal finishing and shaping is very highly developed along mechanical lines and the literature is 20 replete with devices and structures to develop a predetermined form from rough stock. The instant invention, in contradistinction, provides a circuit and associated ap- 25 paratus for removing metal from a blank to be operated upon. For clarity of disclosure the following description will relate to the formation and polishing of gears but it will be understood that the method is equally applicable to any form and metal whatsoever.

Aside from abrasive failure due to foreign matter, it is known that gear tooth failure may be resolved into 30 three categories (a) bending (b) pitting and (c) scoring.

Gear failure is said to be due to one or a combination of these factors (see "Balanced Design for Case Hardened Gears" by J. Maddock in the March 1954 issue of Product Engineering). According to this analysis bending failures can be represented by a fatigue or SN curve. Pitting likewise is a fatigue phenomenon resulting from excessive compressive stresses. Scoring results from high unit pressures, the generation of very high temperatures of short duration, welding, and finally the breaking of the weld as the gears rotate. As the cycle is repeated the parallel rough lines running radially along the face of the teeth become more pronounced.

Fatigue failure is characterized by crystallographic distortions with localized crystal fractures. The atomic bonds are destroyed and submicroscopic cracks appear which enlarge and eventually become easily visible. Each of the above type of failure is thus related to the surface characteristics of the teeth.

Grinding with an abrasive wheel typically produces very fine surface scratches, each of which may constitute a source of concentrated stress and thereby lower the fatigue life of the metal undergoing cyclic stress. Cold working on the surface, if not uniform, may result in an unbalanced stress pattern and such an asymmetrical stress distribution is not conducive to fatigue resistance. There is also the possibility that heat generated in grinding can be the cause of microscopic cracks.

It should be noted that when gear teeth are made of either an extremely hard steel or when the surface thereof has been hardened, the grinding of such material becomes an extremely difficult and slow process, at best. Frequently, marine gears have a Rockwell hardness in excess of C60, and in such cases grinding of such gears by conventional techniques becomes almost impossible. It is emphasized that electrolysis provides a very satisfactory solution to the problem of grinding, and for machining steels of extreme hardness, since the electrolysis process operates as readily with hard steels as with 70 soft steels.

In addition, electrolysis, automatically, the high points

2

on a metal surface are attacked selectively because of greater current distribution or shorter interelectrode distance that exists between these high points and the cathode. The most highly stressed areas are also attacked selectively because they are anodic rather than adjacent areas of the metal surface. Electrolysis, therefore, is a natural means of leveling a surface, rounding edges, and relieving a relatively stressed area.

In addition to these characteristics, there is another which is of value. That is the absence of heat. At no time during metal removal as here taught, is there any noticeable temperature rise, either of the work or the electrolyte. Thus, there is inherent in the electrochemical method the action of forces working in the proper direction to increase fatigue life by removing or avoiding stress risers, cold work, high points which could be subjected to high compressive stresses, and thermal effects leading to microscopic cracks. The causes of bending, pitting, and scoring failures of gears will therefore be substantially reduced by the electrochemical approach.

It is therefore an object of the present invention to provide a process and apparatus for electrochemically removing metal from a member to reduce the same to a predetermined configuration.

Another object is to shape a member into a predetermined form by electrochemical means.

A still further object is to provide a metal surface that is uniform and free from stressed areas.

Yet another object is to improve on the metal working systems now in use.

Other objects and many of the attendant advantages of this invention will be readily appreciated as the same becomes better understood by reference to the following detailed description when considered in connection with the accompanying drawings in which like reference numerals designate like parts throughout the figures thereof and wherein:

FIG. 1 is a schematic representation of the electro-chemical machining system to be hereinafter described;

FIG. 2 is an elevation showing a gear member being formed;

FIG. 3 is an elevation showing another species of tool used for forming gears;

FIG. 4 is an elevation in section of the structure of FIG. 3 turned through 90 degrees; and

FIG. 5 is a longitudinal elevation in section showing a cutting tool.

Referring now to the drawings wherein like reference characters designate like or corresponding parts throughout the several views there is shown in FIG. 1 a variable source of direct current energy 10 having terminals to which respective leads 11 and 12 are connected. The member 13 from which metal is to be removed is supported in any suitable manner and is connected to the positive lead or anode 12. An element 14 disposed adjacent member 13 is supported for translation and rotation with respect thereto and is connected to the negative lead or cathode 11 substantially as shown. An ammeter 15 and a voltmeter 16 are connected in the circuit in the usual way for determining circuit parameters. A tank 17 is provided for containing a suitable electrolyte and a pump 18 discharges the electrolyte through a pipe 19 to spray the areas of contact between member 14 and element 13.

When the circuit is connected as shown and the element 14 is moved relative to the member 13 metal is removed from the member by electrochemical action, and a final predetermined shape can be realized. The member has been shown in the form of a gear for purposes of illustration of the method but any desired final configuration may be realized.

In practicing the above method the best results are ob-

tained in the current density range from 100 amperes to 600 amperes per square inch. If rapid metal removal is desired current densities as high as 1040 amperes per square inch have been found to produce deep etching. In general the lower the current density the longer is required to remove a given quantity of metal, and the more uniform the final surface.

The relative speed between the moving bodies is preferably maintained between 4700 to 5200 linear feet per minute for best results.

The electrolyte used in the electrochemical machining process offers an additional variable. It has been found that certain electrolytes which permit high metal removal rates result in deep etching action particularly on soft metals. Other selected electrolytes are slower in metal removal rates but provide a more uniform final surface. The following electrolytes, having the slow working characteristics referred to above, are cited by way of example: 5% NaNO₃ plus 1% NaNO₂, and 5% NaNO₃ plus 5% Na₂S₂O₃. All electrolytes should be inhibited to 20 protect the work and tools against corrosion, as for example, an oil-in-water emulsion containing about 1% of an emulsifiable naphthenic oil. Sodium silicate solutions have been used and are satisfactory except for the formation of glassy deposits upon drying. As a specific example of the results obtained a finish of 7 to 9 microinches R.M.S. was obtained on tool steel having a hardness of Rockwell C60.

In the description of FIG. 1 above, no mention was made of the engagement between the relatively moving members. The several parts however are in contact, one with another and extreme care must be exercised in the control of this factor to prevent mechanical abrasions removing more metal than is removed by the electrochemical action. If a conforming negatively connected element, or cathode, is not used then line contact may result with the positively connected work, or anode. Line contact introduces difficulty in the control of pressure of the cathode on the anode and control of current density. Due to line contact, pressures can be extremely high and if not carefully regulated mechanical abrasion may become excessive and a series of fine surface scratches may result. FIG. 2 illustrates a conforming cathode.

In FIG. 2 the positive lead 12 is connected through slip rings (not shown) to the work or anode 13. The negative lead 11 connects to cathode 20 and pipe 19 is depended upon to furnish an electrolyte to the interengaging surfaces. Metal is removed from the anode by electrochemical action, as previously discussed, and the cathode is shaped to conform to the final configuration of the gear teeth substantially as shown. Thus at the start of the metal removing process the contact may be of somewhat limited area and mechanical abrasion and electrolytic erosion may result, however, this is not deemed material until the final configuration is approached whereupon the area of contact greatly increases, substantially as shown, and an extremely uniform final surface is obtained.

FIGS. 3 and 4 taken together show respective views of a worm hob 21 used to generate cooperating teeth in a wormwheel 22. As in above discussed variants the work is connected to the positive terminal of a source of direct current energy and the hob is connected to the negative terminal thereof. Nozzles 19 continuously supply electrolyte to the interengaging metal surfaces and upon moving the members relative one to another metal will be removed from the anode connected member to thereby form it into a predetermined shape.

FIG. 5 illustrates a type of tool which has been successfully used in this novel metal working system. Ref-
